Primary Examiner — Leanne Was-Englehart*Assistant Examiner* — Sherry L Jones(74) Attorney, Agent, or Firm — Nitin Kaushik(57) CLAIM

The ornamental design for a smart cat litter box, as shown and described.

DESCRIPTION

FIG. 1 is a front perspective view of a smart cat litter box, showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view.

The broken lines in the drawings depict portions of the smart cat litter box that form no part of the claimed design.
